UNITED STATES PATENT OFFICE.

PATRICK CONNOLLY, OF NEW YORK, N. Y.

FLUID-SUPPLY FITTING.

No. 833,025.

Specification of Letters Patent.

Patented Oct. 9, 1906.

Application filed December 18, 1902. Renewed July 25, 1906. Serial No. 327,751.

To all whom it may concern:

Be it known that I, PATRICK CONNOLLY, a citizen of the United States, residing at New York city, county of Kings, and State of New York, have invented certain new and useful Improvements in Fluid - Supply Fittings, fully described and represented in the following specification and the accompanying drawings, forming a part of the same.

10 The object of this invention is to provide an improved fitting specially adapted for forming hot and cold water connections for laundry-tubs, although the invention is not to be limited to use with laundry-tubs or for 15 forming hot and cold water connections.

A full understanding of the invention can best be given by a detailed description of preferred constructions embodying the various features thereof, and such a description 20 will now be given in connection with the accompanying drawings, showing such a preferred construction.

In said drawings, Figure 1 is a longitudinal sectional view of the preferred form of fitting, 25 showing the same attached to the partition of a compartment-tub. Fig. 2 is a section on line 2 of Fig. 1. Fig. 3 is a longitudinal sectional view of a modified construction. Fig. 4 is a section on line 4 of Fig. 3.

30 Referring to the drawings, 10 represents a casing provided with inlet-openings 11 and 12 at one end, which when the fitting is used for hot and cold water supply will be connected with hot and cold water supply pipes 35 in any suitable manner. The casing is divided interiorly by a partition 13, running from a point between the inlet-openings 11 and 12 into two chambers 15 and 16, and each side of the casing shown, which is intended for use on a partition of a compartment-tub, is provided with outlet-openings 40 19 and 20 from the chambers 15 and 16, respectively, these outlet-openings being adapted to receive suitable outlet-cocks 21. The 45 casing is preferably of rectangular form and is intended to be secured to the partition of a compartment-tub for the purpose of supplying hot and cold water to compartments on each side of the partitions. Preferably the 50 partition 25 will be cut away to receive the casing, as shown in Fig. 1, so that the top of the casing will lie flush with and form a continuation of the top of the partition, and the casing is preferably formed on the bottom and front end with flanges 26 for extending 55 on each side of the partition to hold the

casing in position. The casing is preferably formed at its back end with a downwardly-extending lug 27, provided with an opening for receiving a screw or bolt for fastening the 60 casing to the tub. The casing is also preferably formed to extend a short distance beyond the back wall of the tub, and this extension preferably extends slightly downward from the main portion of the casing, so 65 that the inlet-openings 11 and 12 may be far enough apart for convenient attachment of the supply-pipes, while permitting the top of the casing to be of less depth than would otherwise be necessary in order to provide 70 for such convenient attachment of the supply-pipes.

The partition 13 is preferably of such a form—for example, as shown in Fig. 1—as to permit the outlet-openings 19 and 20 to be 75 placed in line parallel with the top wall of the casing, so that the outlet-cocks will be positioned parallel with the top of the tub-partition.

Figs. 3 and 4 show a slightly-modified 80 construction, in which the casing is not formed to extend backward beyond the rear wall of the tub and in which downwardly-extending wings 30 are provided on the casing for securing the casing in place by bolts 85 31, extending through said wings and the tub-partition. In this figure also the casing is shown as having instead of the side outlet-openings 19 and 20 top outlet-openings 32 and 33 in the top wall of the casing for receiving vertical and branching faucets 34 and 35, each formed with branching outlet ends for supplying both compartments of the tub. 90

It will be understood that the invention is not to be limited to the exact construction 95 and form of the fitting, as shown in the drawings for the purpose of illustrating the invention and to which the foregoing description has been mainly confined, but that the invention includes changes and modifications 100 thereof within the claims.

What I claim is—

1. A fitting for forming connections, as for hot and cold water, for compartment-tubs, formed of a casing having two inlet-openings 105 at one end and a partition dividing the interior of the casing into two compartments with which the inlet-openings respectively communicate, and having in both sides of the casing an outlet-opening from each compartment, substantially as described.
2. A fitting for forming connections, as for

hot and cold water, for compartment-tubs, formed of a casing adapted to be set into the partition between two compartments of the tub and having flanges for extending on either side of the partition, said casing having two inlet-openings at one end and a partition dividing the interior of the casing into two compartments with which the inlet-openings respectively communicate, and having in both sides of the casing an outlet-opening from each compartment, substantially as described.

3. A fitting for forming connections, as for hot and cold water, for compartment-tubs, formed of a casing having two inlet-openings at one end and a partition dividing the interior of the casing into two compartments with which the inlet-openings respectively communicate, and having in both sides of the casing an outlet-opening from each compartment, the outlet-openings in each side of the casing being arranged in line parallel with the top of the casing, substantially as described.

25 4. A fitting for forming connections, as for hot and cold water, formed of a casing adapted to be set into the wall of a tub, and having two inlet-openings at one end and a partition extending from between the inlet-openings to a point on the top wall of the casing and dividing the interior of the casing into two compartments with which the inlet-openings respectively communicate, and having an outlet-opening from each of said compartments, substantially as described.

35 5. A fitting for forming connections, as for hot and cold water, formed of a casing adapted to be set into the wall of a tub, and having two inlet-openings at one end and a partition dividing the interior of the casing into two compartments with which the inlet-openings respectively communicate, and having outlet-openings in the side of the casing, one from each of said compartments, substantially as described.

45 6. A fitting for forming connections, as for hot and cold water, for compartment-tubs, formed of a casing having a partition dividing the interior of the casing into two compartments, a back extension of a greater depth than the main portion of the casing,

inlet-openings to said back extension communicating with the two compartments respectively, and having in both sides of the casing an outlet-opening from each compartment, substantially as described. 55

7. A fitting for forming connections, as for hot and cold water, formed of a casing having a partition dividing the interior of the casing into two compartments, a back extension of a greater depth than the main portion of the casing, inlet-openings to said extension communicating with the two compartments respectively, and having an outlet-opening from each of said compartments, substantially as described. 65

8. A fitting for forming connections, as for hot and cold water, formed of a casing having two inlet-openings at one end and a partition extending from between the inlet-openings to a point on the top wall of the casing and dividing the interior of the casing into two compartments, and having an outlet-opening from each compartment, substantially as described. 75

9. A fitting for forming connections, as for hot and cold water, formed of a rectangular casing having two inlet-openings at one end and a partition dividing the interior of the casing into two compartments with which the inlet-openings respectively communicate, and having an outlet-opening from each of said compartments, said outlet-opening being arranged in line parallel with the top of the casing, substantially as described. 85

10. A fitting for forming connections, as for hot and cold water, formed of a rectangular casing having two inlet-openings and a partition dividing the interior of the casing into two compartments with which the inlet-openings respectively communicate, and having an outlet-opening from each of said compartments, said outlet-openings being arranged in line parallel with the top of the casing, substantially as described. 95

In testimony whereof I have hereunto set my hand in the presence of two subscribing witnesses.

PATRICK CONNOLLY.
